United States Patent Office.

ROYAL M. BASSETT, OF DERBY, CONNECTICUT, ASSIGNOR TO HIMSELF
AND THEODORE S. BASSETT, OF SAME PLACE.

Letters Patent No. 64,737, dated May 14, 1867.

IMPROVEMENT IN ROLLING-MILLS.

The Schedule referred to in these Letters Patent and making part of the same.

TO ALL WHOM IT MAY CONCERN:

Be it known that I, ROYAL M. BASSETT, of Derby, of New Haven county, in the State of Connecticut, have invented certain new and useful Improvements in Rolling-Mills; and I do hereby declare that the following is a full and exact description thereof, reference being had to the accompanying drawings, making part of this application.

My invention relates to a novel method of adjusting the lower roll of ("three higher rolls") of rolling-mills. Previous to my invention it has been customary to regulate or adjust the lower roll by means of a vertically arranged screw-shaft working in a nut set into the lower portion of the frame, with its upper end bearing against the lower side of the journal-box, and its lower end formed with a suitable head by which it could be turned. There are several and serious objections to this method of adjusting the lower roll, among which may be mentioned the liability of the screw to work down (and allow the box to get out of adjustment) by the heavy jar of working the rolls, and the great inconvenience arising from having to get down into the "pit," which is always wet, to work the adjusting screw. All these objections I effectually overcome by my invention, (which also involves less expense of construction,) which consists in forming or providing the lower box with an inclined lower surface, and the employment of an adjustable horizontally-arranged wedge which may be drawn back and forth in its seat by a screw-shaft provided with a hand-wheel above the "pit," as will be hereinafter more fully described.

To enable those skilled in the art to make and use my invention, I will proceed to describe it more fully, referring by letters to the accompanying drawings, in which—

Figure 1 is an elevation of a mill (or set of rolls) mounted according to my invention; and

Figure 2 is a detail sectional view at the line *z z*, fig. 1.

In the several figures the same parts are designated by the same letter of reference.

A is the frame of the mill (or one of them) mounted in the usual manner on the bed-plate *B*, and between which frames, and under the rolls, is formed the usual "pit." The frames are connected at *c c* by rods or braces in the ordinary manner. *D*, *E*, and *F* are the journals respectively of the top, middle, and lower rolls of a "three-high" set of rolls. The middle roll has its journals supported by boxes *H H* in the usual manner, (with the exception of a peculiarity of the box which I will presently explain,) and the upper roll has its journals working in bearings *G g*, the lower one of which is supported by the pendent rods *z z*, and the upper half, *G*, held down and adjusted downward by a screw-shaft *T*, in a manner familiar to those acquainted with this class of machinery. The journals of the lower roll are mounted in boxes, one of which is seen at *I k*. These boxes may be formed each with an inclined lower face, *k*. Under each of these boxes is arranged, to slide longitudinally, a wedge-shaped block *L*, (which bears on the frame at *w*.) and each of these wedge-shaped blocks *L* is provided with a screw-rod, *P*, which extends along through a suitable box at *g*, and is provided with a hand-wheel, *S*, as shown at fig. 1. As it becomes necessary to raise the lower roll or allow it to descend, the hand-wheels *S* are turned in one or the other direction, as desired, and the wedge-shaped blocks drawn in one or the other direction, to wedge up or let down the boxes *I k*. I have previously alluded to a peculiarity in the construction and application of the boxes which I will now explain. By reference to fig. 2 it will be seen that the flange portion *V* of the box *G* is on the outer side or face of the frame *A*. The bolts *o* project outward from the frame *A*, and through vertical slots *m* (see fig. 1) in the flange portion of boxes, so that by turning up the nut and jamb-nut on bolts *o* the boxes may be set up against the shoulders of the rolls (as they wear) and so that whenever it becomes necessary to take out the boxes they can be all withdrawn from their seats in the frames *A* without disturbing the frames, which cannot be done where the boxes have their flanged portions on the inner (or adjacent) sides of the said frames.

In explaining more particularly the operation of my invention, I need refer only to the adjusting mechanism of lower roll, as this constitutes the feature of my invention. It will be understood, then, that by simply turning the hand-wheels *S*, the screw-shafts *P* will be made to slide the wedge-shaped supporting blocks *L*, which effect the lowering and raising of the boxes *I*. And it will be seen that since the angle of the wedges is slight, (with a horizontal line,) the jarring on them cannot, while they are held by the screw *P*, change the

positions. The hand-wheels S extend up above the pit, so that the workman does not have to go down into the wet to handle the adjusting device; and by means of my invention I can dispense with the large screw and nut formerly used, and thus very much reduce the cost of the apparatus.

Having fully explained my invention, what I claim as new in rolling-mills, and desire to secure by Letters Patent, is—

The employment, in combination with the box, of the lower roll, of the adjusting wedge L, inclined seat K, screw-shaft P, and hand-wheel S, or its equivalent, the whole to operate as specified, for the purpose set forth.

In testimony whereof I have hereunto set my hand and seal this 21st day of July, 1866.

ROYAL M. BASSETT. [L. S.]
